INVENTOR

Victor J. Evans

ATTORNEY

WITNESS:

UNITED STATES PATENT OFFICE.

FRED F. SOMERS, OF STURGIS, MICHIGAN.

BRACKET.

Application filed May 23, 1925. Serial No. 32,414.

This invention relates to means for supporting shade rollers and curtain poles, the general object of the invention being to provide a pair of brackets with arms thereon for supporting a shade roller and with other arms for receiving the ends of a curtain supporting member.

Another object of the invention is to so arrange the parts that the shade roller will 10 be hidden by the curtain.

This invention also consists in certain other features of construction and in the combination and arrangement of the several parts, to be hereinafter fully described, illustrated in the accompanying drawings and 15 specifically pointed out in the appended claim.

In describing my invention in detail, reference will be had to the accompanying 20 drawings wherein like characters denote like or corresponding parts throughout the several views, and in which:—

Figure 1 is a plan view showing the device in use.

Figure 2 is a perspective view of one of 25 the brackets.

Figure 3 is a view of a portion of the other bracket.

Figure 4 is a sectional view through Fig- 30 ure 1.

In these views, the brackets are shown at 1, each bracket comprising a plate 2, the arm 3 and the pair of arms 4, the arms being formed integral with the plate. The 35 arm 3 is of angle shape and has a head 5 at its outer end. The head of one bracket is provided with a slot 6 and the head of the other bracket is provided with a hole 7 for receiving the pintles of the shade roller A.

The arms 4 are arranged one on each side 40 of the arm 3 and each arm has a rounded

enlargement 8 at its outer end, the enlargements of the two arms extending in opposite directions. These arms are adapted to enter the open end of the telescopic curtain 45 supporting member B, each section of which is of angle shape.

From the foregoing, it will be seen that the supporting arms for both the shade roller and the curtain pole are formed integral 50 with the supporting plate 2, which is provided with the holes 2' for receiving the fastening means so that it is only necessary to use a pair of brackets to support both the shade roller and the curtain pole. The parts 55 are so arranged that the curtain will hide the shade roller.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A supporting bracket of the class described, comprising a base plate, an angle arm formed therewith and having a head provided with a pintle receiving opening 70 and a pair of straight arms formed with the base plate, one on each side of the angle arm, for supporting a curtain pole, each straight arm having a rounded enlargement at its outer end the first arm extending from the center of the plate and the other arms extending from the outer edge of the plate and said central arm being longer than the other arms.

In testimony whereof I affix my signature.

FRED F. SOMERS.
